(Cl. D26—14)

FIG. 1.

FIG. 2

FIG. 3

FIG. 4

FIG. 5

FIG. 1 is a front, top, and right side isometric view of a portable stereo tape recorder or similar article with the cover removed;

FIG. 2 is a bottom view of the unit shown in FIG. 1;

FIG. 3 is a bottom, front, and right side isometric view showing the unit when supplied with its front cover;

FIG. 4 is a rear, bottom, and right side isometric view shown in reduced scale;

FIG. 5 is a right end elevation further reduced, the opposite side being a mirror image thereof.

The right and left components on opposite sides of the center console comprise respective speaker enclosures which may be physically separated from the center console and, when separated, connect to the latter solely by respective electrical speaker cords.

What we claim is:

The ornamental design for a portable stereo tape recorder or similar article, substantially as shown and described.
